DRAFTING MACHINE

Charles H. Little, Cleveland Heights, Ohio, assignor of one-tenth to Charles Hubbard Little, Cleveland Heights, Ohio.

Application August 5, 1933, Serial No. 683,773

18 Claims. (CL 33—79)

The present invention relates to drafting machines of the parallel motion type, wherein an arm comprising a plurality of connected sections or parallelograms is employed to maintain parallelism of rulers and protractors as they are moved about a drawing board, and particularly to those drafting machines wherein the sections or parallelograms are of the wheel and band type.

A very high degree of accuracy is required in machines of this character, and due to the particular construction thereof, slight errors or changes in the various parts, especially the parallelograms, results in multiplied errors at the rulers. Arms of the wheel and band type can be made to give very accurate parallelism to the rulers but their use has been very limited because of the elasticity of the bands which results in instability or springiness at the ends of the rulers. The present invention overcomes this serious defect without interfering with the free and easy movement of the arm, which is essential for both accuracy and convenience of operation.

Arms of the wheel and band type usually comprise two sections or parallelograms, each of which comprises a pair of equal diameter wheels rotatably connected to each other by either a single or double strut and carrying a taut band.

An object of the present invention is the provision of a band for a wheel and band type parallel motion mechanism that will have a high resistance to tension, compared with its resistance to turning about the wheels, and also not require excessive tension to keep it taut. A number of means for obtaining this result will be herein described but the preferred construction consists of a single band of flexible material wrapped several times about the wheels with the ends and certain intermediate parts thereof clamped or fastened to the wheels. The band may be provided with transverse curvature, which construction reduces the amount of tension required to keep the same taut, and also tends to keep the several layers in alignment with each other. Multiple bands are also shown, which have a larger cross-section between the wheels than that of the portion which turns about the wheels, provided with adjusting means for properly distributing the stresses among the several bands. This latter construction is very advantageous in arms having longer sections or parallelograms than are ordinarily used.

Another object of the present invention is the provision of a novel drafting machine, comprising a wheel and band type arm in which the band

has a high resistance to tension, compared to its resistance to turning about the wheels.

Another object of the present invention is the provision of a novel drafting machine of the parallel motion type in which the protractor and handle lie much closer to the drawing board than the protractor and handle of machines of the prior art.

Another object of the present invention is the provision of a novel drafting machine of the parallel motion type comprising a wheel and band type of arm in which the center of the protractor is external of the band.

Further objects and advantages of the invention will be apparent to those skilled in the art from the following description of the preferred embodiments thereof described with reference to the accompanying drawings, in which

Fig. 1 is a plan of a drafting machine embodying the present invention, attached to a drawing board;

Fig. 2 is a side elevation of the drafting machine and drawing board shown in Fig. 1;

Fig. 3 is a section on the line 3—3 of Figs. 1 and 4, with portions in elevation;

Fig. 4 is a section on the line 4—4 of Fig. 3, with portions in elevation;

Fig. 5 is a plan of the band shown in Figs. 1 to 7 inclusive;

Fig. 6 is an enlargement of a portion of Fig. 1;

Fig. 7 is a section on the line 7—7 of Figs. 1, 2 and 6;

Fig. 8 is a section similar to Fig. 7 illustrating a modified construction of band;

Fig. 9 is a section similar to Figs. 7 and 8 illustrating a further modified construction of band;

Fig. 10 is a plan of a modified construction of drafting machine embodying the present invention;

Fig. 11 is an enlargement of a portion of Fig. 10;

Fig. 12 is a section on the line 12—12 of Fig. 10;

Fig. 13 is a plan of a further modified construction of drafting machine embodying the present invention;

Fig. 14 is a side elevation of the device shown in Fig. 13;

Fig. 15 is an enlargement of a portion of Fig. 14;

Fig. 16 is a section on the line 16—16 of Fig. 15, and

Fig. 17 is an enlargement of one of the adjustable inserts shown in Fig. 13.

Similar reference characters designate corre-

sponding parts throughout the several figures of the drawings.

Referring to the drawings, the drawing boards to which the several drafting machines are shown attached are designated by the reference character B. The drafting machine illustrated in Figs. 1 to 7 inclusive consists of a protractor A carried at one end of an arm C, the other end of which is pivotally attached to an anchor D. The anchor D is of well known construction, and per se forms no part of the present invention and will not be described in detail, suffice it to say that the same is slidably supported on and adjustable along a bar 10 attached to the under-side of the board B by brackets 11.

The anchor parallelogram comprises two wheels 13 and 14 of equal diameter. The upper wheel 13 is fixed to a member 15 pivotally connected to the anchor D in a manner well known in the art, and the lower wheel 14 is connected to a tubular shaft 16, by means of anti-friction bearings 17. The wheels 13 and 14 are spaced apart by means of an adjustable strut 19 provided with forked end members 20 and 21. The upper end member 20 projects to either side of the wheel 13 and is rotatably connected thereto by means of anti-friction bearings in such a manner that it is free to oscillate about the center thereof as an axis. The lower forked end member 21 is connected to the tubular shaft 16 upon which the wheel 14 is rotatably supported.

The wheels 13 and 14 are joined by a flexible band 25 in such a manner that the wheel 14 does not rotate with reference to the drawing board B and the wheel 13, as the strut 19 is oscillated about its pivoted connection. The band 25 runs between flanges on the periphery of the wheels 13 and 14 which assist in retaining the band in position on the wheels, and is connected to each wheel in a manner hereinafter referred to.

The protractor parallelogram comprises two wheels 30 and 31 of equal diameter and similar in construction to the wheels 13 and 14 of the anchor parallelogram. The left-hand wheel 30 is rotatably connected to a tubular shaft 29 by antifriction bearings 32, and the right-hand wheel 31 is pivotally supported by anti-friction bearings, in a forked end member 33 of an adjustable strut 34 similar in construction to the strut 19 previously referred to. The other extremity of the strut 34 is provided with a forked end member 35 which extends on either side of the wheel 30 and is connected to the tubular shaft 29 in such a manner that the strut 34 is free to oscillate about the axis of the wheel 30.

The wheels 30 and 31 are joined by a flexible band 38, similar to the band 25, in such a manner that the wheel 31 does not rotate with reference to the drawing board B and the wheel 30, as the strut 34 is oscillated about its pivoted connection with the tubular shaft 29. The flexible bands 25 and 38 each comprise a single strip of thin flexible material, preferably steel, wrapped about the wheels 13 and 14, and 30 and 31, respectively, a plurality of times. As illustrated, see Figs. 3 and 4, the strips are wrapped about their respective wheels four times. Both ends of the strip which forms the band 38 are attached to the wheel 30 by means of a screw 40 which extends through elongated slots 41 formed in the strip, and the wheel 31 is attached to the band 38 in a similar manner by a screw, not shown, which projects through the elongated slots 42. The strip which forms the band 25 is attached to the wheels 13 and 14 in a similar manner,

The struts 19 and 34 are adjustable for the purpose of assembling the bands on the wheels, and for taking up slack and producing tension in the band. In the embodiment of the invention illustrated, the construction of both struts is the same and the adjustment is accomplished by turning a tubular member 43, see Fig. 4, threaded into the interior of the tubular strut member. A head 44 on the member 43 abuts against the adjacent forked end member which is prevented from turning with reference to the strut by a pin 45. The pin 45 is secured in the tubular strut member and projects through a slot 46 in a short shaft 47 fixed to the forked end member. The tubular member 43 is provided with a knurled hand grasp 48 for easy operation thereof, so constructed that it entirely conceals the thread in all working positions. The bands are adjusted to obtain the proper distribution of tension between the different layers by loosening the screws which attach the same to the wheels, and alternately applying and releasing the tension thereof and oscillating the sections or parallelograms. The elongated slots in the strips through which the screws pass permit the different layers of the band to adjust themselves after which the screws are tightened and the band held securely to the wheels independent of the friction between the band and the wheels. Clips 49 are preferably employed to keep the different layers of the band in alignment, but these clips may be omitted if desired. The clips 49 permit longitudinal movement of the bands relative to each other, and may be held from longitudinal movement along the bands in any convenient manner.

It has been found that one-piece flexible bands wrapped about the wheels a number of times produce a very practical, cheap, and simple band which gives a high degree of stability at the outer end of the scales without adversely affecting the ease of motion of the arm. Multiple bands greatly increase the stability or lack of springiness at the outer end of the rulers by permitting a sufficiently large section to be employed to prevent undue stretch between the wheels without materially increasing the turning resistance when the band wraps and unwraps about the wheels, because the moment of resistance varies as the square of the layer thickness. This construction also reduces the amount of tension required to keep the bands taut and in turn the stresses in the parts between the wheels and the load on the bearings, etc. Attaching the bands to the wheels by means of the screws 40 also reduces these stresses by doing away with the necessity of sufficient friction to prevent the wheels from turning in the bands. The tension in the bands and the stress in the struts often exceeds 200 pounds, and any reduction in the stresses to which the various parts are subjected results in easier turning.

The wheels 14 and 30 are connected together by screws 50 in such a manner that they move as a unit. The position of the screw 50 is limited by the extreme positions of the struts 19 and 34, shown in dotted lines in Fig. 4, as they oscillate a maximum of approximately 180°. A spacer collar 51 is employed to keep the wheels in proper spaced relationship.

A member 55 secured to the underside of the wheel 31 carries the protractor assembly A detachably secured thereto by screws 56. The protractor assembly is of well known construction and per se does not form a part of the present in-

vention and will not be described in detail, suffice it to say that it comprises the protractor proper designated by the reference character 57, a handle 58, and the rulers 59 and 60. The center of the protractor is located externally of the band 38 which construction permits the handle 58 and the hand to lie much closer to the drawing and avoids any interference of the hand of the operator with the band or wheel. This construction is also advantageous when working at the left hand part of the drawing, especially in angular positions, as it places the rulers further from the bands.

Figs. 8 and 9 illustrate two modified constructions of bands 63 and 64 which may be employed in place of the bands shown in Figs. 1 to 7 inclusive. The bands 63 and 64 are similar to the bands 25 and 38 shown in Figs. 1 to 7 inclusive, except for the fact that the bands 63 and 64 are transversely curved. In Fig. 9 one of the layers of the band 64 is shown curved in a reverse direction. Transversely curving the bands as illustrated in Figs. 8 and 9 assists in keeping the various layers in alignment and reduces the amount of tension necessary to keep the bands taut. In some light, small machines, particularly when the transverse curved bands are employed, pin bearings may be used in place of the ball bearings illustrated, thus simplifying the construction and lowering the cost of the machine. The construction shown in Figs. 1 to 10 inclusive is claimed in my copending application Ser. No. 50,215, filed November 16, 1935, entitled "Drafting machine".

Figs. 10 to 12 inclusive illustrate a modified construction of the drafting machine shown in Figs. 1 to 7 inclusive. The drafting machine illustrated in these figures is similar in construction to that shown in Figs. 1 to 7 inclusive and the duplicate parts are indicated by the same reference characters. In place of the multiple bands 25 and 38 employed in the drafting machine first described, multiple bands 67 and 68 of modified construction are employed. The bands 67 and 68 each comprise a plurality of thin flexible strips, one or more of which are provided with inserts having a larger area of cross section than that of the strip proper, and, therefore, less stretch per unit length than the strips themselves. In the embodiment illustrated three strips 70, 71 and 72 are shown although any desired number may be employed.

The outer and inner strips 70 and 72 are connected to parts or inserts 73 and 74 as illustrated. The inserts 73 are made of two parts threaded in opposite directions and connected by a turnbuckle 75. One of these inserts 73 is placed in each of the inner and outer strips of the band so that they may be adjusted for length and the stress in the band equally distributed between the various strips or layers. While no inserts are illustrated in the center strip 71 it will be understood that inserts may be employed in this strip if desired. The bands are preferably attached to the wheels in a manner similar to that described with reference to the bands 25 and 38.

The wheel 76 located at the free or protractor end of the arm is similar in construction to wheel 31 previously referred to, except that it is provided with a rotatable center 77 adapted to be clamped in any adjusted position by screw clamps 78. The protractor assembly A is connected to a member 79 attached to the rotatable center 77 of the wheel 76, and may be adjusted about the center of the wheel 76 as an axis.

The strut 80 in the protractor section or parallelogram is the same in construction as the strut 34 previously referred to, except that the forked end member 33 of the strut 34 is replaced by an end member 81 provided with two spaced rollers 82 which engage the periphery of the wheel 76. A member 83 fixed to the end member 81 projects underneath the wheel 76 between the same and a depressed portion 84 of the member 79. The member 83 does not normally bear against either the wheel 76 or the portion 84 of the member 79 but prevents the wheel from snapping out of position at right angles to the drawing board.

A modified construction of drafting machine having a protractor especially adapted for civil engineering and navigation work, and having its center coincident with the center of the wheel at the free or protractor end of the arm, is illustrated in Figs. 13 to 17 inclusive. The drafting machine illustrated in these figures is similar in construction to the machines previously referred to, and duplicate parts are indicated by the same reference characters. The anchor parallelogram comprises a wheel 90 rotatably connected to a member 91 pivotally connected to the anchor D, and is adapted to be held in any adjusted position by a thumb screw 92, threaded into an aperture in the member 91 and extending through an arcuate slot 93 in the wheel.

An adjustable strut 95, similar in construction to the strut 80 previously referred to, is pivotally connected to the center of the wheel 90. Rollers 96 carried by the strut 95, engage the periphery of a cylindrical member or wheel 97 the diameter of which is equal to the diameter of the wheel 90. The cylindrical member or wheel 97 is twice the thickness of the wheel 90 and is common to both the anchor and protractor sections or parallelograms. The wheel 97 is joined to the wheel 90 and held in engagement with the rollers 96 by means of a multiple band 98 similar in construction to the bands 67 and 68 except that the inserts 73 are replaced by short inserts 99 and the inserts 74 are omitted altogether, giving the machine a larger range of movement. The inserts 99 are employed for the purpose of adjusting the length of the inner and outer layers of the band to the length of the center layer, so that each layer will take its proper proportion of the load.

The protractor section or parallelogram comprises a wheel 100, and an adjustable strut 101 both ends of which are provided with rollers 102 in engagement with the periphery of the cylindrical member or wheel 94 and the periphery of the wheel 100. The wheel 100 is joined to the cylindrical member or wheel 94 by a multiple band 103 similar in construction to the band 98. The bands 98 and 103 are preferably not connected to the respective wheels with which they engage and the movement of the struts is not limited thereby. The elbow of the arm may throw to the opposite side of the center line between the wheels 90 and 100, thus making it possible to get parts of the arm out of the way of the rulers when working in certain positions. The loss of stability at the outer end of the rulers due to the omission of the long inserts of larger area of cross-section between the wheels, is compensated for by the fact that it is desirable to use larger wheels on account of the large size protractor used for civil engineering work, inasmuch as the stability of the outer end of the rulers is proportional to the square of the diameter of the wheels, other things being equal. With the larger wheels it is also

possible to use thicker material for the bands since the bend is not as sharp.

Members 105 and 106, similar in construction, are attached to the struts 95 and 101, respectively, at the ends thereof adjacent the cylindrical member or wheel 87. The member 105 projects over the top surface of the wheel 87 and extends underneath a plate 107 secured to the top of the wheel. The member 106 projects over the under surface of the wheel 87 and extends above a plate 108 secured to the underside of the wheel 87. The members 105 and 106 do not normally engage against either the plates 107 and 108, respectively, or the wheel 87, but prevent the wheel from snapping out of position at right angles to the drawing board.

A protractor ring 112 is rotatably set in the wheel 100 and adapted to be clamped to the wheel in any position by clamping screws 113. The setting of the protractor ring is read from a dead-line mark on a member 114 fixed to the wheel 100. The inner diameter of the protractor ring 112 is made with a V-shape and fits into a corresponding groove in the periphery of a ring composed of four segments 115, 116, 117 and 118 adjustably connected to a central plate 120 by eccentric rivets 121, and an eccentric clamp 122 by which it may be radially locked in any position. A handle 126 is secured to the central plate 120 by screws 126. A ruler plate 128 is connected to the central plate 120 by screws 129 and held in proper spaced relation by tubular members 130. A member 133 attached to the underside of the strut 101 projects beneath the wheel 100 and above the ruler plate 128. The member 133 normally does not engage either the wheel 100 or the ruler plate 128, but prevents the wheel 100 from snapping out of position at right angles to the drawing board.

A spring pressed pawl 135, operated by a thumb piece 136, engages slots in a ring 137 attached to the underside of the protractor ring 112, to give zero, 30, 45, 60 and 90 degree angles as desired. The rulers are indicated by the reference characters 138 and 139. The protractor illustrated is very light and substantial in construction, and does not interfere in any way with any part of the wheel or arm.

The protractor and handle are set very low with reference to the drawing. The construction permits the protractor ring to be set at any desired angle, which is always shown. This is a very desirable feature in a number of instances, for example, the correction of the compass reading at any particular point may be made by turning the ring to compensate for the correction, and then clamping it in position. The readings are then direct and the amount of the correction is always clearly shown.

The preferred embodiments of the present invention have been illustrated and described, but I do not wish to be limited to the particular construction illustrated, which may be varied within the scope of this invention. It is my intention to cover in as broad a way as possible the advantage of the easy moving, stretch resisting bands, giving a high degree of accuracy and stability, and the advantages of low lying protractors, free from interference with the arms. I particularly point out and claim as my invention the following:

1. In a parallel motion mechanism for a drafting machine or the like, a plurality of wheels, a plurality of bands extending around said wheels, and means for adjusting the length of some of

said bands whereby the stresses in the different bands may be equalized.

2. In a parallel motion mechanism for a drafting machine or the like, the combination of a plurality of wheels, a band extending around said wheels, a strut connected to said wheels for holding the same in spaced relationship, and a plurality of rollers interposed between said strut and the periphery of one of said wheels.

3. In a drafting machine the combination of a parallel motion arm, a ruler assembly rotatably connected to one end of said parallel motion arm, a friction clamp slidably supported for movement radially with reference to the axis about which said ruler assembly is rotatably supported, and means for moving said clamp radially to clamp said ruler assembly within said arm.

4. In a drafting machine the combination of a parallel motion arm, a protractor ring connected to one end of said arm, a ruler assembly rotatably supported by said arm concentric with said protractor ring, a friction clamp slidably supported for movement radially of the axis about which said ruler assembly is rotatably supported, and means for moving said clamp to clamp said ruler assembly to said arm in any adjusted position.

5. In a drafting machine the combination of a parallel motion arm, a protractor ring carried by one end of said arm, a ruler assembly rotatably supported by said arm concentric with said protractor ring, said ruler assembly comprising a segmental plate, and means for moving one of the segments of said plate radially to clamp said ruler assembly in any adjusted position.

6. In a drafting machine the combination of a pair of wheels, a flexible band extending around said wheels, a strut operatively connected to said wheels for holding the same in spaced relation, said strut comprising telescoped members having threaded engagement with each other for producing relative longitudinal movement between the same, one of said members having a guard extending over the break between said members for covering the threads which would otherwise be exposed.

7. In a device of the character described the combination of a parallel motion mechanism or arm of the wheel and band type, a member rotatably supported coaxial with the wheel at one end of the parallel motion mechanism or arm, a second member rotatably supported coaxially with the first mentioned member, said first and second member being located at the upper side of the wheel and a ruler arm at the lower side of the wheel fixed to said second member through the center of the wheel.

8. In a drafting machine, the combination of a parallel motion mechanism of the wheel and band type, a protractor ring rotatably supported by the wheel at the free end of said parallel motion mechanism coaxial therewith, a second member rotatably supported by said protractor ring coaxial therewith, said protractor ring and second member being located at the upper side of said wheel, and a ruler arm at the lower side of said wheel fixed to said second member.

9. In a protractor the combination of a supporting member, an annular member rotatably supported by said supporting member, a second member rotatably supported coaxially with said annular member, a handle connected to said second member, a spring actuated means for holding said annular member and said second

- member against relative rotation, and a member adjacent said handle for releasing said means.
10. In a protractor the combination of a supporting member, an annular member rotatably supported by said supporting member, a second member rotatably supported coaxially with said annular member, a detent carried by one of said last two mentioned members adapted to engage the other for preventing relative rotation between the same.
11. In a protractor the combination of a supporting member, an annular member rotatably supported by said supporting member, a second member rotatably supported coaxially with said annular member, a handle connected with said second member, a spring actuated detent for holding the last two mentioned members against relative rotation, and a member adjacent said handle for releasing said detent.
20. 12. In a protractor the combination of a supporting member, an annular member rotatably supported by said supporting member, a second member rotatably supported coaxially with said annular member, a handle connected with said second member, one of the last two mentioned members having a plurality of apertures therein, a detent carried by the other of said members adapted to engage in said apertures, and means adjacent said handle for releasing said detent.
30. 13. In a protractor the combination of a supporting member, an annular member rotatably supported by said supporting member, means for clamping said annular member against rotation within said supporting member, a second member rotatably supported coaxially with said annular member, a handle connected with said second member, spring actuated means for clamping said annular member and said second member against relative rotation, and means adjacent said handle for releasing the last mentioned means.
40. 14. In a protractor the combination of a supporting member, an annular member rotatably supported by said supporting member, a ruler assembly rotatably supported coaxially with said annular member, a handle connected to the ruler assembly, a spring actuated means for holding said annular member and said ruler assembly
- against relative rotation, and a member adjacent said handle for releasing said means.
15. In a protractor the combination of a supporting member, an annular member rotatably supported by said supporting member, a ruler assembly rotatably supported coaxially with said annular member, a handle connected with said ruler assembly, a detent for holding said annular member and said ruler assembly against relative rotation, and a member adjacent said handle for releasing said detent.
25. 16. In a drafting machine the combination of a parallel motion arm of the wheel and band type, a protractor ring member rotatably supported by the wheel adjacent to one end of said parallel motion arm, a member rotatably supported coaxially with said protractor ring member, one of said members having a plurality of notches therein, a detent carried by the other of said members adapted to engage in said apertures for preventing relative rotation between said members.
35. 17. In a drafting machine the combination of a parallel motion arm comprising a plurality of wheels, an annular protractor member rotatably supported by the wheel adjacent to the free end of said parallel motion arm, a ruler assembly rotatably supported coaxially with said annular protractor member, a handle connected to said ruler assembly, said protractor member having a plurality of apertures therein, a detent carried by said ruler assembly adapted to engage in said apertures, and means adjacent said handle for releasing said detent.
45. 18. In a drafting machine the combination of a parallel motion arm of the wheel and band type, an annular protractor member rotatably supported by one of the wheels of said parallel motion arm, means for clamping said annular protractor member against rotation relative to the wheel, a ruler assembly rotatably supported coaxially with said annular member, a handle connected with the ruler assembly, spring pressed means carried by said ruler assembly for clamping said protractor member and said ruler assembly against relative rotation, and means adjacent said handle for releasing the last mentioned means.

CHARLES H. LITTLE.
